PAPER CLAMP

Norihiro Tanaka, Osaka, Japan, assignor to Lihit
Industrial Co., Ltd., Osaka, Japan

Filed Sept. 7, 1972, Ser. No. 287,005

Term of patent 14 years

Int. Cl. D19—04

U.S. Cl. D19—65

FIG. 2

FIG. 1

FIG. 4

FIG. 3

FIG. 7

FIG. 5

FIG. 6

FIG 8

FIG. 1 is a front elevational view of a paper clamp showing my new design;

FIG. 2 is a rear elevational view;

FIG. 3 is a top plan view;

FIG. 4 is a bottom plan view;

FIG. 5 is a right side elevational view;

FIG. 6 is a left side elevational view;

FIG. 7 is a front elevational view showing the paper clamp in an open position; and

FIG. 8 is an enlarged scale perspective view showing the paper clamp in an open position.

I claim:

The ornamental design for a paper clamp, as shown and described.
